(57) **CLAIM**

The ornamental design for a cover portion of electric pallet jack, as shown and described.

DESCRIPTION

FIG. 1 is a perspective view of a cover portion of electric pallet jack shown in condition of use, in accordance with the present invention;

FIG. 2 is a perspective view thereof;

FIG. 3 is a cross-sectional view taken along line 3-3 in FIG. 4 thereof;

FIG. 4 is a front view thereof;

FIG. 5 is a back view thereof;

FIG. 6 is an enlarged first side view thereof;

FIG. 7 is an enlarged opposite second side view thereof;

FIG. 8 is a top view thereof; and,

FIG. 9 is a bottom plan view thereof.

The broken lines showing the electronic pallet jack in FIG. 1 depicts environment and forms no part of the claimed design. All other broken lines depict portions of the cover portion of electric pallet jack that form no part of the claimed design.
